UNITED STATES PATENT OFFICE

PER A. H. ANDERSON, OF CHICAGO, ILLINOIS

SASH CONSTRUCTION

Application filed October 24, 1930. Serial No. 490,894.

This invention relates to improvements in sash construction and has particular relation to a construction for supporting plate glass windows and the like.

One object of the invention is to provide a construction which may be readily assembled to furnish a support for plate glass windows and the like, of the desired rigidity and yet having sufficient resiliency that the glass will withstand all ordinary shocks.

Another object of the invention is to provide a construction of the above-indicated character which shall be simple and economical to manufacture and which shall be adapted to be embodied in a compact design of pleasing appearance.

Other objects and advantages of the invention will appear from a consideration of the following detailed description in conjunction with the accompanying drawings, in which—

Figure 1 is a fragmentary sectional view of a construction embodying the invention, the parts being shown in the positions which they occupy before the glass is finally clamped in position;

Fig. 2 is a view similar to Fig. 1 but showing the parts in the positions which they occupy after the glass has been finally clamped in position;

Fig. 3 is a fragmentary front elevational view of the construction shown in Figure 1, certain of the parts being broken away and shown in section along the line 3—3 of Figure 1;

Fig. 4 is a detailed perspective view of a rockable bracket member used in the construction embodying the invention; and

Fig. 5 is a detailed perspective view of a fixed bracket member used in the construction, and of a resilient member which is secured to said fixed bracket member, as will hereinafter appear.

Referring to the drawings, the sash construction embodying the invention is shown as being mounted upon the usual sill 11 which constitutes a bottom support for the window. A rear support 12 is also shown as being mounted upon the sill 11 but with its front edge set back somewhat from the front

of the sill. It will be understood that this arrangement is a usual form of construction for the mounting of plate glass windows and the like. A gutter molding member 13 is secured in fixed position relative to the sill 11 and rear support 12, by means of screws 14 and 15 respectively entering said sill and rear supporting member. It is not essential that both of these screws be used, as either one will suffice.

The screws 14 and 15 pass through holes in a fixed bracket or supporting member 16, as well as through aligned holes in the gutter molding member 13. The fixed bracket 16 comprises a bottom portion 16^a overlying the top of the sill 11 and an upstanding portion 16^b which extends upwardly parallel to the front face of the rear supporting member 12. This upstanding portion is doubled upon itself, as indicated at 16^c, and this doubled portion has a screw-threaded hole therein to receive a screw 17. These details of construction of the bracket member 16 are more fully illustrated in the detailed view of Fig. 5, from which it will be observed that this member is preferably formed with supporting web portions 16^d and 16^e for the purpose of added strength and rigidity.

The bottom portion 16^a of the fixed bracket 16 has secured thereto by means of rivets 18 a member 19 of resilient metal. This member 19 is secured to the bottom surface of the member 16 and projects forwardly therefrom. The forwardly projecting portion of the member 19 is bent as indicated at 19^a to extend upwardly at a relatively small angle and is then again bent as indicated at 19^b to turn upwardly at a steeper angle of inclination. A downward bend is formed at 19^c so that the outer or forward extremity of the member 19 is of substantially inverted V-formation. The portion of the member 19 which is secured to the bottom of the member 16 is provided with a hole in alignment with the hole in the bottom portion 16^a of the member 16, and the screw 14 may be inserted through these aligned holes.

The gutter molding member 13 has a bottom portion 13^a which is adapted to lie upon the top of the sill member 11 and which is provid-

ed with holes at suitable intervals for reception of the screws 14. A portion 13^b of the gutter molding member extends upwardly along the front face of the rear supporting member 12 and between said rear supporting member and the fixed bracket member 16. The upper extremity of the portion 13^b is doubled over as indicated at 13^c to provide a groove for receiving the upper edge of the member 16 as indicated in Figs. 1 and 2. A portion 13^d extends forwardly from the doubled portion 13^c, and a glass-engaging portion 13^e extends downwardly from the forward extremity of the portion 13^d. The portion 13^d is perforated as indicated at 13^f at suitable intervals to permit access to the screws 17 from above.

A pane of sheet glass or the like is shown at 20 and is adapted to be supported from the bottom by means of blocks 21 of wood or other suitable material. The inner surface of the glass 20 is adapted to be engaged by the glass-engaging portion 13^e of the gutter molding member 13, and the outer surface of the glass 20 is similarly engaged by a glass-engaging portion 22^a of a face molding member 22. This face molding member comprises a front portion 22^b, from the bottom of which a portion 22^c is bent rearwardly to extend toward the front edge of the bottom portion 13^a of the gutter molding member 13. The front portion of the member 22 is preferably bent inwardly as indicated at 22^d for a purpose which will hereinafter appear.

The glass-engaging portion 22^a of the face molding member 22 is bent over a bent portion 23^a at the upper extremity of one of the legs of a substantially V-shaped bracket member 23. The formation of the bent portions 22^a and 23^a of the members 22 and 23 is such that an interlocking connection between these members is provided at this point. The inwardly bent portion 22^a of the member 22 cooperates with a downwardly extending lip portion 23^b of the member 23 to hold the latter member in position without the use of any other fastening means, and yet permits the hereinafter described rocking movement of the member 23 without bending the member 22 outwardly at the bottom thereof.

The bracket member 23 is rockably mounted at its apex upon the resilient forwardly projecting portion of the member 19. The other leg of this rockably mounted bracket member is bent outwardly at its outer extremity to form a portion 23^c lying in a substantially horizontal plane beneath the doubled portion 16^c of the fixed bracket member 16 and in position to be engaged by the screw 17. The construction of the bracket member 23, including reinforcing web portions 23^d, is shown in Fig. 4.

This arrangement is such that when the screw 17 is screwed downwardly, the bracket member 23 will be caused to move in a clock-

wise direction about its rockable mounting on the member 19, whereby the glass-engaging portion 22^a of the face molding member 22 is pressed firmly by the bracket portion 23^a against the outer surface of the glass 20, the inner surface of which is similarly engaged by the glass-engaging portion 13^e of the gutter molding 13. The resiliency of the upwardly bent portion at the front of the member 19 provides a resilient mounting for the bracket member 23, so that the glass 20 is clamped in position by a relatively shock-proof arrangement.

When the screw 17 is turned down to clamp the glass 20 in position, the resilient forward extremity of the member 19 is caused to move downwardly until its downwardly bent end portion engages the rearwardly bent portion 22^c at the bottom of the face molding member 22. In this manner, the face molding member is securely clamped against the sill member 11 when it has assumed the position in which the glass 20 is secured. During the tightening of the screw 17 the rockable bracket member 23 is prevented by the upwardly extending portion of the member 19, between the bends 19^b and 19^c, from moving forwardly more than the desired distance. The positions of the parts when the glass 20 and the bottom of the face molding member 22 are clamped in the desired relation are illustrated in Fig. 2.

During the assembling and adjustment of the construction illustrated, the bottom of the face molding member 22 is prevented from moving rearwardly to a greater extent than desired by portions 13^g of the gutter molding member 13. These portions are struck upwardly from the bottom portion 13^a of said gutter molding member at the forward edge thereof to form abutments adapted to be engaged by the rear edge of the rearwardly bent portion 22^c of the face molding member. With this construction it is impossible for the portion 22^c to ride over the forward edge of the bottom portion 13^a of the gutter molding member, and thus it is assured that the portions 22^c will be brought to bear directly upon the top surface of the sill member 11.

Drainage of water which may condense upon the inner surface of the glass 20 is provided for by perforations in the top forwardly extending portion 13^d of the gutter molding member 13, such a perforation being indicated at 13^h in Fig. 3. The face molding member 22 is similarly perforated at its front lower corner, as indicated at 22^e in Figs. 1 and 3. Any water which drains into the interior of the sash construction is thus permitted to drain out at the front lower corner thereof.

It will be understood that the construction illustrated and described herein is adapted to be utilized along all of the edges of a plate glass window or the like. The description and illustration are applied to the sash construc-

tion as utilized at the bottom of the glass, and the terms indicating relative positions of parts and directions in which the various portions thereof extend have been selected 5 for the description of this particular arrangement. It is to be understood, therefore, that similar terms are used in the following claims merely for convenience of expression, and that such terms are to be interpreted as covering constructions at the sides and top of 10 the glass in which corresponding arrangements of parts are utilized.

While only one specific embodiment of the invention has been shown and described herein, it will be apparent to those skilled in the art that various changes and modifications 15 in the details of construction and arrangement of parts may be made without departing from the spirit and scope of the invention, as set forth in the appended claims.

What is claimed as new and is desired to be secured by Letters Patent, therefore, is:

1. In a sash construction, a pair of members adapted to embrace the marginal portion 25 of a glass pane, an angular bracket engaging one of said members, a resilient support on which said bracket is rockably mounted, and means for rocking said bracket on said support to cause said members to clamp 30 a glass pane therebetween.

2. In a sash construction, a pair of members adapted to embrace the marginal portion of a glass pane, a bracket of substantially V-shaped cross-section rockably supported at its apex and having one leg engaging one of said members, and means for rocking 35 said bracket about its apex to cause said members to clamp a glass pane therebetween.

3. In a sash construction, a pair of members adapted to embrace the marginal portion of a glass pane, a bracket of substantially V-shaped cross-section rockably supported at its apex and having one leg engaging one of said members and the outer portion of 45 its other leg bent outwardly to lie in a substantially horizontal plane, a fixed support, and a screw carried by said fixed support and engageable with the horizontal portion of said rockably mounted bracket to press said 50 one of said members into clamping relation to a glass pane between it and the other of said members.

4. In a sash construction, a pair of members adapted to embrace the marginal portion of a glass pane, a bracket of substantially V-shaped cross-section rockably supported at its apex and having one leg engaging one of said members and the outer portion of its other leg bent outwardly to lie in a substantially horizontal plane, a fixed support having a portion doubled upon itself and lying in a substantially horizontal plane above the outwardly bent portion of said bracket, and a screw carried by the doubled 55 portion of said fixed support and engageable

with said outwardly bent portion of said bracket to press said one of said members into clamping relation to a glass pane between it and the other of said members.

5. In a sash construction, a bottom support, a face molding member having a glass-engaging portion at its upper extremity and extending downwardly from said portion into close relation to said bottom support, a rockable bracket member having a portion engaging the glass-engaging portion of said face molding member, and a support for said rockable bracket member comprising a portion secured in fixed position relative to said bottom support and a resilient portion upon 60 which said bracket member is rockably supported.

6. In a sash construction, a bottom support, a face molding member having a glass-engaging portion at its upper extremity and extending downwardly from said portion into close relation to said bottom support, a rockable bracket member having a portion engaging the glass-engaging portion of said face molding member, and a support for said rockable bracket member comprising a portion secured in fixed position relative to said bottom support, a resilient portion upon 65 which said bracket member is rockably mounted, and a clamping portion for holding said face molding member in fixed position relative to said bottom support.

7. In a sash construction, a bottom support, a face molding member having a glass-engaging portion at its upper extremity and having its lower extremity bent rearwardly to lie upon said bottom support, a bracket member of substantially V-shaped cross-section rockably supported at its apex and having one leg engaging said face molding member adjacent the glass-engaging portion thereof, means for forcing the other leg of said V-shaped member downwardly to cause the first-mentioned leg to press the glass-engaging portion of said face molding member 70 against the glass, and a support for said V-shaped member comprising a portion secured in fixed position relative to said bottom support, a resilient portion upon which the apex of said V-shaped member is rockably supported, and a clamping portion overlying the rearwardly bent portion at the bottom of said face molding member and adapted to clamp the latter in fixed position relative to said bottom support upon depression of said resilient portion resulting from forcing said V-shaped member downwardly.

8. In a sash construction, a face molding member and a gutter molding member adapted to embrace the marginal portion of a glass pane, a bracket of substantially V-shaped cross-section rockably supported at its apex and having one leg engaging said face molding member, and the outer portion of its other leg bent outwardly to lie in a substan- 75

tially horizontal plane, a fixed support having an upstanding portion, part of which is doubled upon itself to lie in a substantially horizontal plane above the outwardly bent portion of said bracket, a screw carried by the doubled portion of said fixed support and engageable with said outwardly bent portion of said bracket to press the glass-engaging portion of said face molding member into clamping relation to a glass pane between it and the glass-engaging portion of said gutter molding member, said gutter molding member comprising a portion extending along the upstanding portion of said fixed support with its upper extremity doubled over the upper extremity thereof to form a rigid supporting contact therewith, and a portion extending forwardly from said doubled portion to the glass-engaging portion, said forwardly extending portion overlying said screw and being apertured to permit access to said screw.

9. In a sash construction, a bottom support, a face molding member having a glass-engaging portion at its upper extremity and having its lower extremity bent rearwardly to lie upon said bottom support, a gutter molding member secured in fixed position relative to said bottom support and having a glass-engaging portion at its upper extremity and a bottom portion lying upon said bottom support, said bottom portion having portions struck upwardly therefrom at intervals along its forward edge to be engaged by the rearward edge of the rearwardly bent lower extremity of said face molding member to limit the rearward movement of the latter.

10. In a sash construction, a bottom support, a face molding member having a glass-engaging portion at its upper extremity and extending downwardly from said portion into close relation to said bottom support, a rockable bracket member having a portion engaging and interlocked with the glass-engaging portion of said face molding member, and a support for said rockable bracket member comprising a portion secured in fixed position relative to said bottom support and a resilient portion upon which said bracket member is rockably supported.

In witness whereof, I have hereunto subscribed my name.

PER A. H. ANDERSON.
